SLING SHOT GRIP

Original Filed Sept. 9, 1948

Henry L. Beggs INVENTOR.

BY Loyal J. Miller

ATTORNEY

UNITED STATES PATENT OFFICE

163,738

SLING SHOT GRIP

Henry L. Beggs, Oklahoma City, Okla.

Substituted for abandoned design application Serial No. 148,513, September 9, 1948. This application October 5, 1950, Serial No. 12,468

Term of patent 14 years

(Cl. D34—15)

To all whom it may concern:

Be it known that I, Henry L. Beggs, a citizen of the United States, residing at Oklahoma City, in the county of Oklahoma and State of Oklahoma, have invented a new, original, and ornamental Design for a Sling Shot Grip, of which the following is a specification, reference being had to the accompanying drawing forming part hereof.

Figure 1 is a perspective view of the front face of a sling shot grip, showing my new design;

Figure 2 is a similar view with the device turned slightly toward the left hand from the position in which it is viewed in Fig. 1;

Figure 3 is a perspective view looking slightly downward upon the rear face of the device; and,

Figure 4 is a similar view with the device

turned slightly toward the left hand from the position in which it is viewed in Fig. 3.

I claim:

The ornamental design for a sling shot grip, as shown.

HENRY L. BEGGS.
